(57) **CLAIM**

The ornamental design for a portable kneeling altar, as shown and described.

DESCRIPTION

FIG. 1 is a perspective view of a portable kneeling altar showing my new design;

FIG. 2 is a front elevational view thereof;

FIG. 3 is a rear elevational view thereof;

FIG. 4 is a top plan view thereof;

FIG. 5 is a side elevational view thereof, the opposite side being the same in appearance; and,

FIG. 6 is a bottom plan view thereof.
